Inventor:

Andrew Miller Belfield

UNITED STATES PATENT OFFICE.

ANDREW MILLER BELFIELD, OF CHICAGO, ILLINOIS, ASSIGNOR TO WILLIAM D. PENNINGTON AND JOHN R. PENNINGTON, OF CHICAGO, ILLINOIS.

CLOCK BANK.

Application filed August 8, 1925. Serial No. 49,141.

My invention relates to clock banks, and particularly to coin controlled clock banks.

One of the objects of the present invention is to provide a simple, practical and effective construction of clock bank.

Another object of the invention is to arrange for the control of the device by a coin so that the device will be useful only when coins are deposited in it from time to time for saving.

Another object of the invention is to assure the deposit of the coin used for controlling the bank and so prevent the bank from being controlled for continued and repeated running by a single coin, thereby assuring saving of the coins.

In the accompanying drawings Fig. 1 is a view of the rear of the upper portion of a clock bank embodying my present invention;

Fig. 2 is a view of the front of the same; Fig. 3 is a cross sectional view taken on line 3—3 in Fig. 1;

Fig. 4 is a view similar to Fig. 1 with a portion of the casing of the bank removed.

Referring to the drawings I show a bank having a casing 1 containing a clock 2 whose face 2^a appears through an aperture or opening in the front of the bank casing.

The clock winding stem 3 projects from the back of the bank and is provided with a thumb piece 4 by which it may be turned. A coin slot 5 is also provided in the back of the bank casing for the insertion of coins to be used to control the bank.

The winding stem 3 is broken, as shown in Fig. 3, and composed of two parts 3^a and 3^b whose ends are toothed or serrated so that they may fit together to form in substance a single operative stem, it being apparent that

the stem 3 is inoperable for purposes of winding the clock when the two parts are separated, as shown in Fig. 3, but may be used for that purpose when said two parts are joined together by the intermeshing or

locking of their toothed ends, as by pushing the stem portion 3^a inwardly against the spring 7 which tends to push and maintain said stem portion 3^a in an outward or retracted position.

The stem portion 3^a is normally held against inward motion by a trigger or locking device 8 in the form of a bell crank lever pivoted at 9, one end 8^a of which device 8 fits in a groove 10 in the stem portion 3^a.

The other end 8^b of the bell crank 8 pro-

jects into a coin chute 11 whose lower portion extends downwardly in the clock casing and whose upper end is bent rearwardly so that its end opening corresponds with the coin slot 5. Thus a coin deposited in the coin chute 11 will fall downwardly and strike the end 8^b of bell crank 8, and thereby depress said end 8^b against the action of spring 12 tending to hold said member 8^b in elevated position. The weight and force of the coin, however, swings said member 8^b downwardly so that the coin may pass by its end down further into the coin chute and in so doing the bell crank member 8^a is swung down the groove 10, thereby releasing stem portion 3^a and permitting insertion of said portion 3^a inwardly, and when said stem portion is pushed inwardly so as to connect with the other stem portion the clock may be wound by turning the winding key 3.

The device is arranged, however, so that this winding of the clock automatically causes the deposit of the coin, thereby assuring the saving of the coin and preventing it from being used again for the purpose of effecting a winding of the clock. To this end a coin holding device 13 preferably in the form of a bell crank lever pivoted at 14 is provided, one end 13^a of said device being held by spring 15 against the end of the coin chute 11, as a result of which arrangement the coin after having dropped into the chute and swung the lever 8^b downwardly, falls and rests upon the end of arm 13^a and is held in position by such arm, as shown in dotted lines in Fig. 4. In this position the lever arm 8^b is held in a swung down position, thereby permitting the clock to be wound a full winding or any predetermined extent of winding. When this winding is accomplished the coin holding device 13 is actuated however, so as to swing the member 13^a downwardly and permit the coin to drop into the bottom of the clock casing, or into some suitable receptacle, thereby assuring the deposit and saving of the coin and preventing it from being used to effect a further winding or partial winding of the clock, it being seen that when this operation occurs the coin passes down below the end of lever arm 8^b and thereby permits spring 12 to pull said lever arm 8^b upwardly and again cause lever arm 8^a to engage groove 10 in winding stem portion 3^a as soon as winding stem 3 is released, due to action of spring 7.

105
110

This actuation of the coin holding device 13 is accomplished by a pin 17 on arm 18 carried by shaft 19 which is gear connected for rotation with the winding stem or spring 5 drum of the clock, as by providing shaft 19 with gear 20 meshing with the pinion 21 on winding stem portion 3^b. As a result the winding of the clock slowly turns shaft 19 and when the clock has been wound the full 10 or predetermined extent, pin 17 strikes lever 13^b and swings it to the right, (Fig. 4), thereby swinging member 13^a downwardly and releasing the coin in chute 11, so that said coin is deposited and its saving assured 15 and it is removed so that it cannot be used again to effect a winding operation of the clock.

The deposit of another coin in the coin chute will similarly swing member 8^b downwardly to permit winding of the clock by 20 winding stem thumb piece 4 and when this winding has taken place the coin will be automatically deposited and the mechanism restored to inward position ready for the insertion of another coin to permit a further 25 winding of the clock.

No attention need be paid to the coin after it has once been inserted, nor any attention given to the clock winding mechanism, 30 it simply being necessary to insert the coin and then wind the clock, the coin automatically permitting the clock to be wound a full or predetermined amount and then automatically deposited without further act or attention on the part of the user or winder of the clock.

It will be understood that changes and modifications may be made without departing from the spirit of the invention.

40 What I claim is:

1. A clock bank having a split winding stem, spring means tending to separate the parts of the stem, a coin operated device normally holding the stem parts apart, but arranged to be tripped by the coin to permit winding of the clock and means whereby the turning of the winding stem deposits the coin.

50 2. A clock bank having a split winding stem, spring means tending to separate the parts of the stem, a coin operated device normally holding the stem parts apart, but arranged to be tripped by the coin to permit winding of the clock and means whereby the turning of the winding stem deposits the coin, said last mentioned means comprising a pivoted lever spring controlled to hold the coin 55 against deposit and a pin rotatable by the turning of the winding stem to actuate said lever and withdraw it from position below the coin.

60 3. A clock bank having in combination, a coin chute, a bell crank lever having one end

in the coin chute to be struck by an inserted coin, spring means tending to hold said lever in position, but adapted to allow the coin to pass down the chute and be in turn held in downward position by the coin, a transversely split winding stem having its parts provided with means for connection with one another, spring means tending to force said parts apart, one of said parts being engaged by the other arm of said bell crank lever so 70 as to hold it away from the other part, said lever releasing said part and permitting the stem parts to be united when said lever is struck, and depressed by a coin, a second bell crank lever arranged in connection with the 75 coin chute and adapted to hold the coin in position in the chute after it has struck the first mentioned lever and depressed the same, gear connections between the normally disengaged part of the winding stem and the clock 80 winding mechanism whereby the clock may be wound on turning the connected stem, a crank arm and shaft gear connected to said disengaged part of the winding stem, said crank having a pin arranged to strike the 85 other end of the second mentioned bell crank lever and so swing the same as to allow the coin to fall from the coin chute to be deposited and also to release the first mentioned bell crank lever, and spring means tending to hold said second mentioned lever in 90 position to hold the coin against deposit.

4. In a coin bank the combination of a split winding stem and a lever device arranged to be tripped by the coin and to control the separation and connection of the parts of the winding stem, and spring means tending to separate the parts of the winding stem.

5. In a clock bank the combination of a coin chute, a spring controlled trigger having one end in the chute, a split winding stem one of the parts of which has a groove receiving the portion of said trigger, the latter being adapted to normally occupy said 110 groove but to be moved out of the same by the deposit of a coin in the chute, and spring means tending to push said winding stem part away from the other split part.

6. In a clock bank the combination of a coin chute, a spring controlled trigger having one end in the chute, a split winding stem one of the parts of which has a groove receiving the portion of said trigger, the latter being adapted to normally occupy said groove but to be moved out of the same by the deposit of a coin in the chute, spring means tending to push said winding stem part away from the other split part, and power transmitting connections between said winding stem and the winding mechanism.

7. In a clock bank the combination of a coin chute, a spring controlled trigger having one end in the chute, a split winding stem one of the parts of which has a groove 130

receiving the portion of said trigger, the latter being adapted to normally occupy said groove but to be moved out of the same by the deposit of a coin in the chute, spring ⁵ means tending to push said winding stem part away from the other split part, power transmitting connections between said wind-

ing stem and the winding mechanism, and means operable by said connections for depositing the coin.

In witness whereof, I hereunto subscribe my name this 7th day of August, A. D., 1925.

10

ANDREW MILLER BELFIELD.
